UNITED STATES PATENT OFFICE

150,488

DESIGN FOR A COMBINED PUTTY KNIFE
AND GLASS CUTTER

Walter R. Amstutz, Chicago, Ill., assignor to
Butler Brothers, Chicago, Ill., a corporation of
Illinois

Application February 20, 1947, Serial No. 137,053

Term of patent 14 years

(Cl. D93—4)

To all whom it may concern:

Be it known that I, Walter R. Amstutz, a citizen of the United States and a resident of Chicago, in the county of Cook and State of Illinois, have invented a new, original, and ornamental Design for a Combined Putty Knife and Glass Cutter, of which the following is a specification, reference being had to the accompanying drawing, forming part thereof:

Figure 1 is a perspective view of a combined putty knife and glass cutter showing my new design.

Figure 2 is a plan view thereof.

Figure 3 is a side elevational view thereof, and
Figure 4 is an end view thereof.

I claim:
The ornamental design for a combined putty
knife and glass cutter, substantially as shown.

WALTER R. AMSTUTZ.
